A. R. HAVENER

RIVET SETTING MACHINE

Filed April 5, 1926

FIG. 2.

FIG. 3.

FIG. 4.

FIG. 5.

FIG. 6.

Inventor:
Arthur R. Haverer
by his atty.

Charles S. Gooding

UNITED STATES PATENT OFFICE.

ARTHUR R. HAVENER, OF WAYLAND, MASSACHUSETTS, ASSIGNOR TO JUDSON L. THOMSON MANUFACTURING CO., OF WALTHAM, MASSACHUSETTS, A CORPORATION OF MASSACHUSETTS.

RIVET-SETTING MACHINE.

Application filed April 5, 1926. Serial No. 99,812.

This invention relates to an improved riveting machine and especially to that portion of the riveting machine embodying an anvil and a work support co-operating therewith.

5 The object of the invention is to provide a rivet setting machine for setting bifurcated rivets in the soles of boots and shoes in such a manner that there will be a space between the clinched prongs of the rivet and the upper face of the sole, the said rivet serving as a means, as hereinafter more fully set forth, for attaching a metal shank to a sole.

10 The invention consists in the improved anvil and work support, and in the combination of the same with the positioning and driving instrumentalities of a rivet setting machine, as set forth in the following specification and particularly in the claims thereof.

15 20 Referring to the drawings:—

Figure 1 is a front elevation of my improved anvil and work support shown in operative relation to the driver and rivet carrier of a rivet setting machine similar to that disclosed in the patent to Joseph E. Per- 25 rault, No. 879,896, patented February 25, 1908, "machine for setting rivets."

Fig. 2 is a sectional elevation taken on the line 2—2 of Figure 1.

30 Fig. 3 is a sectional elevation similar to Fig. 2, but showing the rivet carrier lowered and with the rivet about to be driven through the material by the driver.

Fig. 4 is a detail section showing the rivet as it appears just after being clinched.

35 Fig. 5 is a detail section taken on the line 5—5 of Fig. 4.

Fig. 6 is a perspective view of the work support.

40 Fig. 7 is a plan view of a sole with the rivet inserted therein and a shank shown in full lines in the position which it occupies when being attached to the sole and in dotted lines in the position in which it appears after 45 being attached to the sole.

Like numerals refer to like parts throughout the several views of the drawings.

50 In the drawings, 10 is a portion of the head of a rivet setting machine. 11 is the rivet driver, 12 the rivet carrier slide, 13 and 14 the rivet carrier fingers, 15 and 16 the springs supporting said fingers upon the

slide 12. 17 is a rivet positioning arm pivoted at 18 to the carrier slide 12 and held normally in the position illustrated in Figure 1 by a spring 19 also fast to the carrier slide 12, all of this mechanism being old and well known in the art.

55 A cylindrical anvil 20 is positioned on a portion of the frame 21 and is adjustable vertically by means of a screw 22 having screw-threaded engagement with the frame 21. On the upper end of the anvil 20 is fixedly mounted a cap 23 having a hollow cylindrical portion or neck 24 and a top 25. 60 The cap 23 is provided in the top with a slot 26 which extends through the top in alignment with the anvil 20 and extending transversely thereof. The top 25 of the work support is also provided with a groove 27 65 which extends transversely of the slot 26 upon opposite sides thereof, the bottom of the groove 27 being inclined downwardly from the upper face of the top 25 into the slot 26. 70

75 The object of the slot 26 is to allow the rivet prongs, after they have been clinched by the anvil, to be withdrawn through the top of the cap.

80 The object of the groove 27 is to prevent a portion of the material into which the rivet is driven from being cut off by the edge of the slot, in which case it would be possible to rotate the rivet in the material in which it is set and this would be very undesirable as it 85 would free one end of the shank 28.

85 The shank 28 is positioned upon the sole 29 as illustrated in Fig. 7. Said shank is provided with a slot 30 extending longitudinally thereof, and when it is desired to position the shank upon the sole and attach it thereto, it is first placed in the position illustrated in full lines, Fig. 7, and the prongs 31 of the rivet 32 are then in alignment with the slot 30. Upon rotating the shank 28 90 from the full line to the dotted line position, Fig. 7, the prongs of the rivet will be positioned across the slot 30, the tack 33 is then inserted through the shank and into the sole 29 to hold the other end of the shank in position on the sole. The slot 30 allows play 95 of the free end of the shank relatively to the sole when the shoe is being used.

100 A reciprocatory motion is imparted to the

driver 11 and to the carrier slide 12 by mechanism well known to those skilled in the art and illustrated in said Letters Patent.

The general operation of the mechanism hereinbefore described is as follows:—

Assuming the parts to be in the relative positions illustrated in Figure 1, the rivets 32 are positioned one by one upon the arm 17, being fed from a raceway in any suitable manner, as for example, in the manner illustrated and described in said Letters Patent, and the operator places the sole 29 upon the top of the work support 28, the sole extending, longitudinally thereof, from right to left in Figure 1. He then places his foot upon the treadle and the rivet carrier and driver move downwardly from the position illustrated in Fig. 2 to that illustrated in Fig. 3. The arm 17 tips upon the pivot 18 and is withdrawn from between the prongs of the rivet. The fingers 13 and 14 are spread apart by the downward movement of the driver 11 and by the head of the rivet, so that the prongs of the rivet 25 are driven through the material of the sole 29 and are clinched or spread outwardly as illustrated in Fig. 4 by the anvil 20. The position of the rivet relatively to the material of the sole is illustrated in Fig. 4 and in Fig. 5, Fig. 5 particularly illustrating how the material of the sole is pushed down into the groove 27 on opposite sides of the slot 26 without cutting it off.

When the driver 11 and carrier slide 12 have moved upwardly together with the rivet carrying fingers 13 and 14 and the arm 17, the parts assume again the position illustrated in Fig. 1 and the sole 29 is removed from the machine. Now the sole has a rivet 32 firmly attached thereto with the prongs 31 of the rivet extending transversely of the sole as illustrated in Fig. 7 and ready to have a shank attached to the sole in the manner hereinbefore set forth.

I claim:—

1. A rivet setting machine having, in combination, an anvil and a work support extending across the top of said anvil, the work support being provided with a slot extending transversely of the anvil and with a groove in its upper face intersecting said slot on opposite sides thereof.

2. A rivet setting machine having, in combination, a stationary anvil and a work support fixedly mounted on the upper end thereof and extending across said upper end, the work support being provided with a slot

extending transversely of the anvil and with a groove in its upper face intersecting said slot on opposite sides thereof.

3. A rivet setting machine having, in combination, an anvil and a cap fixedly mounted on and extending across the upper end thereof and constituting a work support, the cap being provided with a slot in its upper end extending transversely of the anvil and with a groove in its upper face intersecting said slot on opposite sides thereof.

4. A fastener setting machine having, in combination, an anvil, and a work support positioned thereabove provided with a slot extending transversely of the anvil through which the end of the inserted fastener may pass and having a groove extending transversely of the slot on its upper face, the portions of the groove lying on the opposite sides of the slot being provided with inclined bottom surfaces whereby to provide surfaces upon which the work may be pushed by the inserted fastener without danger of shearing action thereon.

5. A rivet setting machine having, in combination, an anvil and a work support extending across the top of said anvil, the work support being provided with a slot extending transversely of the anvil and with a groove in its upper face intersecting said slot on opposite sides thereof, and rivet positioning and driving instrumentalities adapted to insert a two-pronged rivet in material positioned on said work support and to spread the prongs of said rivet against said anvil and spaced apart from said material by the top portion of said work support.

6. A rivet setting machine having, in combination, an anvil and a work support fixedly positioned thereon extending across and adjacent thereto, the work support being provided with a slot extending through the top thereof and transversely of the anvil and with a groove in its upper face intersecting said slot on opposite sides thereof, and rivet positioning and driving instrumentalities adapted to insert a bifurcated rivet in material positioned on said work support and to spread the prongs of said rivet against said anvil, the outer ends of said prongs being spaced apart from the lower face of said material by the top portion of the work support.

In testimony whereof I have hereunto set my hand.

ARTHUR R. HAVENER.
